US0D1012310S

(12) **United States Design Patent** (10) **Patent No.:** **US D1,012,310 S**
(45) **Date of Patent:** **** Jan. 23, 2024**

(54) **REAGENT CARTRIDGE**

(71) Applicant: **Beckman Coulter, Inc.**, Brea, CA (US)

(72) Inventors: **Juan Fernandez de Castro**, Miami, FL (US); **Giancarlo Ermoli**, North Miami Beach, FL (US); **Thomas Breen**, Coral Springs, FL (US)

(73) Assignee: **Beckman Coulter, Inc.**, Brea, CA (US)

(**) Term: **15 Years**

(21) Appl. No.: **29/868,378**

(22) Filed: **Nov. 30, 2022**

Related U.S. Application Data

(62) Division of application No. 29/724,466, filed on Feb. 14, 2020, now Pat. No. Des. 975,312.

(57) **CLAIM**

The ornamental design for a reagent cartridge, as shown and described.

DESCRIPTION

FIG. 1 is a top isometric view of a reagent cartridge;
FIG. 2 is a right side view thereof;
FIG. 3 is a left side view thereof;
FIG. 4 is a rear view thereof;
FIG. 5 is a front view thereof;
FIG. 6 is a top view thereof;
FIG. 7 is a bottom view thereof;
FIG. 8 is a bottom isometric view;
FIG. 9 is another top isometric view;
FIG. 10 is another bottom isometric view; and,
FIG. 11 is a cross sectional view taken along line 11-11
shown in FIG. 6.
